DOOR SUSPENSION AND ACTUATING
MEANSEmil H. Piron, New York, N. Y., assignor to
Transit Research Corporation, a corporation of
New York

Application December 10, 1938, Serial No. 244,936

6 Claims. (Cl. 268—30)

This invention relates to folding doors for public vehicles such as street railway cars and has for its object to provide a set of door leaves and an improved door operating mechanism therefor which will open the leaves in such manner as to make available a passageway of maximum width which will not require the cutting away of a door step to form door wells.

Another object of this invention is to provide folding door pivotally mounted top and bottom for translation and rotation, in combination with means remote therefrom for causing such translation and rotation.

Doors of the type herein contemplated are ordinarily supported top and bottom on levers upon the ends of which each door leaf is pivotally mounted, the two levers of each leaf being rigidly connected to a vertical shaft located adjacent one edge of the leaf and rotatable therewith to move the door to open and closed positions. An object of this invention is to remove the vertical or actuating shaft entirely out of the passageway and to locate it, preferably, in an inconspicuous place, as for instance, interiorly of an existing stanchion.

Another object is to provide a door leaf guide comprising upper bearing and supporting means together with a lower bearing which acts only as a guide, the lower bearing being made of self-lubricated rubber.

Other objects and advantages will become more fully apparent as reference is had to the accompanying drawing wherein my invention is illustrated, and in which:

Fig. 1 is a top plan view of two door leaves together with the supporting and actuating means therefor constructed according to my invention, and with the parts shown in door closing position.

Fig. 2 is a view similar to Fig. 1 with all parts in door opening position.

Fig. 3 is a front elevation of the doors in closed position with the bearings and other parts of the actuating mechanism in section, and

Fig. 4 is a detail section of the main operating shaft and its housing.

More particularly 1 and 2 indicate the left and right door leaves, respectively, of the type commonly used on street cars, buses and the like. The leaf 1 is supported by a shaft 3 mounted for rotation in and support by a lever arm 4, and the leaf 2 is supported by a shaft 5 mounted for rotation in and support by a lever arm 6. The arm 4 is fixedly mounted on the shaft 3 as are, also, the arms 7 and 8 and the arm 6 is fixedly

mounted on the shaft 5 along with the arm 8, the arms 4, 7 and 8 being rotatable with the shaft 3 which is supported at its upper end by a thrust bearing 10a, and the arms 6 and 9 are rotatable with their shaft 5 which is supported by a thrust bearing 11a. The outer ends of the arms 8 and 9 are pivotally connected to links 12 and 13 which are, in turn, pivotally connected to a common arm 14 on diametrically opposite sides of its pivotal support 15. The arm 8 is pivotally connected to an actuating link 16 which link is pivotally connected also to an arm 17 fixedly mounted for rotation with a vertical shaft 18. The shaft 18 is remote from the door leaves 1 and 2 and is housed, preferably, by a stanchion 19.

The lower part of each door leaf has a pin 20 aligned, respectively, with the pins 3 and 5, on which the leaves can rotate. Each pin 20 is fixedly mounted in an arm 21 fixedly mounted on a vertical shaft 22 for rotation therewith in a self-lubricating bearing 23, usually made of rubber impregnated with graphite, paraffin, castor oil or the like. One of the shafts 22 is connected to a lever arm 24 and the other of which is fixedly connected to a similar lever arm 25. The levers 24 and 25 are pivotally connected to links 26 and 27, respectively, which links are pivotally connected to the ends of an arm 28 on diametrically opposite sides of a journal shaft 29. The shaft 29 is in axial alignment with the shaft 15. The shaft 22 below the leaf 1, is fixedly secured also to an arm 30 which is pivotally connected to one end of a link 31, the other end of which is pivotally attached to an arm 32 fixedly secured to the shaft 18.

The shaft 10 is in axial alignment with one pin 22 and the other shaft 5 is in axial alignment with the other pin 22.

The operation is as follows: The shaft 18, which is out of the range of swinging of the door leaves, may be rotated manually or from a power means applied against the arm 33 thus rotating the outer end of the arm 17 through an arc toward and away from the shaft 10. The link 16 actuated by the arm 17 rotates the arm 7 which is rigidly connected with the shaft 3 and hence rotates the arms 4 and 6. Rotation of the arm 8 also actuates the linkage 12, 14, 13, 9 and 6 and hence causes movement of both door shafts 3 and 5 through an arc having a radius equal to the length of the arms 4 and 6. In order to guide the leaves two pins 34 and 35 are carried by the leaves 1 and 2 respectively for guiding movement in the slots 36 and 37, respectively, in

the top door sill 38. As the pivots 3 and 5 rotate about the shafts 10 and 11 the pins 34 and 35 cause that part of each leaf immediately below them to follow the slots 32 and 33, while the other edge 39 of each leaf moves in a line parallel with the door opening side wall indicated by the dotted lines 40. In view of the fact that the space between the upper and lower leaf supports is entirely unobstructed the leaves or any part thereof can move transversely across the axes of these supports. The final position of the leaves, therefore, can be normal to the original position thus opening the doorway to a maximum, and the outwardly exposed edges of the leaves can extend outwardly of their original position,—that is outwardly of the sidewalls of the vehicle body, so that the inner edges 39 will come to rest immediately in front of the first step leading upwardly from the doorway without requiring that the ends of this first step be cut away.

What I claim is:

1. The combination of a door leaf adapted to close an opening, said leaf being mounted for rotation about an axis, means for translating said axis through an arc described about a second axis located inwardly from both the side of the opening and the closed plane of the door, and means for rotating and translating said leaf, said two axes being so disposed relative to one another that the leaf moves across said second axis during translation of the first axis and into a plane parallel with and in close proximity to the side of the opening.

2. The combination of a door leaf adapted to close an opening, said leaf being mounted for rotation about an axis closely adjacent the vertical mid section thereof, means for translating said axis through an arc described about a second axis located inwardly from both the side of the opening and the closed plane of the door, and means for rotating and translating said leaf, said two axes being so disposed relative to one another that the leaf moves across said second axis during translation of the first axis and into a plane parallel with and in close proximity to the side of the opening.

3. The combination of a door leaf adapted to close an opening, supporting pins having a common axis about which said leaf rotates, arms on one end of each of which one of said pins is mounted, aligned bearings supporting the other ends of said arms and having a second common axis about which said arms rotate located inwardly from both the side of the opening and the closed

plane of the door, and means rotating said arms about said second axis, said arms being so disposed that upon rotating and translating said leaf a portion of said leaf moves across said second axis and into a plane parallel with and in close proximity to the side of the opening.

4. The combination of a door leaf adapted to close an opening, said leaf being mounted for rotation about an axis, means for translating said axis through an arc described about a second axis located inwardly from both the side of the opening and the closed plane of the door, and means for rotating and translating said leaf, said two axes being so disposed relative to one another that the leaf moves across said second axis during translation of the first axis and into a plane parallel with and in close proximity to the side of the opening, said last named means comprising a shaft parallel to said first and second axes and located at a distance from said leaf in any of its positions.

5. The combination of a door leaf mounted for rotation about an axis paralleling its length, aligned bearings arranged one above and one below said leaf, said bearings being spaced laterally from the normal plane of the leaf in its closed position, arms supporting said leaf and journaled in said bearings for translating said axis during rotation of said leaf, said arms being of a length such that translation of the leaf causes movement thereof between the bearings, and a shaft remote from said leaf rotatable about its own axis and having means connected to each of said arms for simultaneous rotation thereof.

6. The combination of a door leaf for closing an opening, said leaf being supported for rotation about a vertical axis closely adjacent its mid section, arms supporting said door, one at the top and the other at the bottom of said leaf, said arms each being of a length substantially less than half the width of the door and being fixedly secured to aligned, rotatably mounted shafts so disposed that axis of the shafts is spaced inwardly from the side of the opening and spaced from the normal plane of the leaf and traversed by a portion of said leaf during leaf opening and closing movements, actuating arms connected to each of the first named arms for rotation thereof, and an elongated shaft fixedly secured to both of said actuating arms, said elongated shaft being mounted for rotation about its own axis.

EMIL H. PIRON.
